(57) **CLAIM**

(21) Appl. No.: **29/260,418**

The ornamental design for a motorized truck/utility vehicle shaped ear plug container with a rotating belt clip, or similar article, as shown and described.

(22) Filed: **May 25, 2006**

DESCRIPTION

(51) **LOC (8) Cl.** 03-01

FIG. 1 is a top plan (closed position) view of a motorized truck/utility vehicle shaped ear plug container with a rotating belt clip, or similar article, showing my new design.

(52) **U.S. Cl.** **D3/203.1**

FIG. 2 is a left end elevational (closed position) view thereof.

(58) **Field of Classification Search** D3/203.1,

D3/203.7, 215, 218, 294, 238; D6/515; D24/106;

206/221, 37-38, 229; 221/186; D21/549;

D12/82-86

See application file for complete search history.

FIG. 3 is a front elevation (open position) view thereof.

(56) **References Cited**

FIG. 4 is a left end elevational (open position) view thereof. Broken lines are representative of ear plugs not part of my claim; and,

U.S. PATENT DOCUMENTS

FIG. 5 is a front elevational (closed position) view showing my new design.
